COMBINATION WINDOW AND VENETIAN
BLIND

George R. Smith, Modesto, Calif.

Application June 28, 1947, Serial No. 757,802

7 Claims. (Cl. 160—107)

1

This invention is directed to, and it is an object to provide, a novel combination window and Venetian blind; the window including an inner and outer pane mounted in spaced relation in a dust-proof casing, and the Venetian blind being mounted in said casing between the panes.

The combination provides a weather proof window especially desirable for air-conditioned homes, offices, etc., and in addition the Venetian blind is mounted in an attractive, out-of-the-way position where it is not subject to dust accumulation and soiling, as are conventional, exposed Venetian blinds.

Another object of the invention is to provide a window and Venetian blind combination, as above, which includes novel mechanism for mounting and actuating the Venetian blind, the blind actuating means being normally enclosed but accessible to the operator without in any way opening the window compartment in which the tilt rail, and vertically adjustable, blind assembly is suspended.

An additional object of the invention is to provide a window and Venetian blind combination, as described, which also includes a novel arrangement for the passage of ventilating air from the outside to the inside of the building independently of the assembly of the casing-supported panes and Venetian blind therebetween.

It is also an object to provide a combination window and Venetian blind which is relatively simple in structure, readily and economically manufactured, and easy to maintain when in use.

It is a further object of the invention to provide a practical and convenient combination window and Venetian blind, and one which will be exceedingly effective for the purpose for which it is designed.

These objects are accomplished by means of such structure and relative arrangement of parts as will fully appear by a perusal of the following specification and claims.

In the drawings:

Fig. 1 is an outside elevation of the combination window and Venetian blind.

Fig. 2 is an enlarged fragmentary inside elevation, partly in section, of said combination window and Venetian blind.

Fig. 3 is a fragmentary sectional plan view on line 3—3 of Fig. 2.

Fig. 4 is a fragmentary sectional elevation on line 4—4 of Fig. 2.

Fig. 5 is a fragmentary sectional elevation on line 5—5 of Fig. 2.

Fig. 6 is a fragmentary plan, mainly in sec-

2

tion, of the detachable coupling at one end of the tilt rail.

Referring now more particularly to the characters of reference on the drawings, the combination window and Venetian blind comprises a rectangular casing, indicated generally at 1, said casing being separated by an intermediate partition 2 into a relatively wide window compartment 3, and a relatively narrow vertical compartment 4 along one side of said window compartment.

The window compartment 3 is closed or defined by an outer, glass pane 5 and an inner, glass pane 6. The panes 5 and 6 are mortised into corresponding portions of the casing 1, and are retained in place by securing and sealing strips 7, whereby the window compartment 3 is weather and dust proof. The panes are flush with the walls.

20 The vertical compartment 4 is closed on the outside by a louvered panel 8 secured to the casing 1 and including a backing screen 9. On the inside, the vertical compartment 4 is normally closed by a vertically hinged door 10 adapted to open inwardly for access to said compartment 4.

The intermediate partition 2 is formed with a vertically spaced pair of ports 11 and 12. The port 11, which is normally closed by a removable plug 13, is provided for access from the vertical compartment 4 into the window compartment, as occasion may demand. The port 12 is for the purpose of ventilating the window compartment 3 to prevent condensation on, or steaming of, the panes 5 and 6; this ventilating port 12 having a removable or replaceable filter pad 14 therein to prevent entry of dust into the window compartment 3.

40 A Venetian blind assembly, indicated generally at 15, is suspended in the window compartment 3, and is constructed and mounted as follows:

A pair of brackets 16 and 17 depend from the headboard 18 of the casing into the window compartment 3 in transversely spaced relation. A tilt rail 19 extends between the lower ends of the depending brackets 16 and 17, being supported at the left-hand end by an end pin 20 carried in a holding notch 21 in the bracket 16. 45 At its opposite end the tilt rail 19 is supported by a detachable coupling, indicated generally at 22, from the adjacent end of an aligned spindle 23 journaled in the lower end of the depending bracket 17 and extending through a bearing 24 50 in the intermediate partition 2.

55

The detachable coupling 22, as shown in detail in Fig. 6, comprises a compression spring 25 engaged between the bracket 17 and a floating end head 26 having projecting pins 27 which seat in matching sockets 28 in the adjacent end of the tilt rail 19. It is thus evident that the compression spring 25 normally urges the tilt rail 19 into frictional engagement with the depending brackets 16, whereby to maintain the blind assembly in adjusted position. The detachable coupling 22 also facilitates initial installation, as well as subsequent removal, of the tilt rail for repair or replacement of the blind assembly.

Suspension or ladder tapes 29 are secured to, and depend from, the tilt rail 19; such ladder tapes 29 tiltably supporting the blind slats 30 in the usual manner.

The raising and lowering control mechanism comprises a horizontal top shaft 31 journaled at one end in a bearing 32 on the depending bracket 16 and supported, at its opposite end, by a detachable coupling 33 formed in part on the adjacent end of an alined spindle shaft 34 carried in a bearing 35 mounted in the partition 2. The detachable coupling 33 comprises a non-circular shank 36 on the horizontal top shaft 31 and a socket 37 on the spindle 34.

The detachable coupling 33 facilitates initial installation, as well as subsequent removal for replacement or repair, of the top shaft.

The horizontal, top shaft 31 carries a pair of transversely spaced spools 38 having lifting ribbons or tapes 39 running thereoff downwardly through slots 40 in the tilt rail 19, one side of said slots carrying a protective facing 41 to prevent undue wear on the corresponding lifting ribbon 39. The lifting ribbons 39 extend downwardly through slots 42 in the blind 33 and connected, at their lower ends, with the bottom rail 43.

It will be seen that with rotation of the spindle 23 and corresponding portion of the tilt rail 19, the angle of the slats 30 will be adjustable, while rotation of the spindle 34 and horizontal top shaft 31, with the lifting ribbons 39 running on or off the spools 38, will cause raising or lowering of the blind.

The spindles 23 and 34 are adapted to be rotated by the operator through the medium of sprockets 44 and 45 mounted on said spindles in the vertical compartment 4. Said sprockets 44 and 45 are rotated by means of chains 46 and 47 running thereover and fitted at opposite ends with pull eyes 48, as shown. Thus, to adjust the blind either for tilt or vertically, the operator need only open the door 10 and then manipulate one or the other of the chains 46 or 47. As is obvious, this can be accomplished without in any way gaining access into the window compartment 3, which remains dust-proof, with the Venetian blind assembly unsoiled in its position between the glass panes 5 and 6.

When it is desired to obtain ventilation between the outside and inside of the building structure, the door 10 is opened, whereby air may flow through the vertical compartment 4 between the louvered panel 3 and the then open door 10. In this manner room ventilation can be accomplished without exposing the Venetian blind to dust accumulation and soiling; this being a very advantageous and valuable feature. The removable plug 13 in access port 11, and the filter pad 14 in port 12, assure against dust entry into the window compartment 3.

It should also be noted that the two-pane window, together with the relatively static air there-

between, tends to limit heat exchange through the structure, which is valuable where the room is air conditioned.

If desired, a check valve and fitting can be substituted for filter 14, so that the dead air may be evacuated from the window compartment to further eliminate dust, dirt, and moisture.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claims.

Having thus described the invention, the following are claimed as new and useful, and upon which Letters Patent are desired:

1. A combination window and Venetian blind, comprising a casing including an intermediate substantially solid partition dividing the casing into a window compartment and a separate compartment along one side thereof, spaced inner and outer panes on the casing enclosing the window compartment, a Venetian blind assembly suspended from the casing in the window compartment and wholly enclosed therein, and adjustment mechanism for the Venetian blind assembly wholly enclosed within the side compartment and being manually operable only from within said side compartment; said side compartment being closed on the inside by a door, and means

extending through the partition and supported therein and connecting the blind assembly in driven relation with the adjustment mechanism.

2. A combination window and Venetian blind, comprising a casing including an intermediate

substantially solid partition dividing the casing into a window compartment and a separate compartment along one side thereof, spaced inner and outer panes on the casing enclosing the window compartment, a Venetian blind assembly suspended from the casing in the window compartment, and adjustment mechanism for the Venetian blind assembly manually operable from within said side compartment; said side compartment being closed on the inside by a door, and on the outside by a ventilation panel, the partition being provided with a ventilating port therethrough, and a filter unit disposed in said port.

3. A combination window and Venetian blind, comprising a casing including a substantially solid intermediate partition dividing the casing into a window compartment and a separate compartment along one side thereof, spaced inner and outer panes on the casing enclosing the window compartment, a Venetian blind assembly suspended from the casing in the window compartment, and adjustment mechanism for the Venetian blind assembly including spindles projecting through said intermediate partition into the side compartment, and means in said side compartment connected to the spindles to manually and selectively rotate the same.

4. A combination window and Venetian blind, comprising a casing including a substantially solid intermediate partition dividing the casing into a window compartment, and a separate compartment along one side thereof, spaced inner and outer panes on the casing enclosing the window compartment, a Venetian blind assembly in the window compartment, and mechanism suspend-

ing the Venetian blind assembly from the casing for tilting and vertical adjustment manually from within said side compartment; said mechanism including a horizontal top shaft, a horizontal tilt rail therebelow, the top shaft being rotatable to vertically adjust the Venetian blind assembly and the rail being tilttable to adjust the angle of the blinds, vertically spaced spindles alined with the top shaft and tilt rail and projecting through the intermediate partition, means detachably connecting adjacent ends of the top shaft and tilt rail with corresponding ends of the spindles, and means in the side compartment arranged for manual operation to selectively rotate said spindles.

5. A combination window and Venetian blind, comprising a casing including a substantially solid intermediate partition dividing the casing into a window compartment, and a separate compartment along one side thereof, spaced inner and outer panes on the casing enclosing the window compartment, a Venetian blind assembly in the window compartment, and mechanism suspending the Venetian blind assembly from the casing for tilting and vertical adjustment manually from within said side compartment; said mechanism including a horizontal top shaft, a horizontal tilt rail therebelow, the top shaft being rotatable to vertically adjust the Venetian blind assembly and the rail being tilttable to adjust the angle of the blinds, vertically spaced spindles alined with the top shaft and tilt rail and projecting through the intermediate partition, means connecting adjacent ends of the top shaft and tilt rail with corresponding ends of the spindles, and means in the side compartment arranged for manual operation to selectively rotate said spindles; the connecting means for the top shaft being a detachable coupling including a non-circular shank removably engaged in a matching socket.

6. A combination window and Venetian blind, comprising a casing including a substantially solid intermediate partition dividing the casing into a window compartment, and a separate compartment along one side thereof, spaced inner and outer panes of the casing enclosing the window compartment, a Venetian blind assembly in the window compartment, and mechanism suspending the Venetian blind assembly from the casing for tilting and vertical adjustment manu-

ally from within said side compartment; said mechanism including a horizontal top shaft, a horizontal tilt rail therebelow, the top shaft being rotatable to vertically adjust the Venetian blind assembly and the rail being tilttable to adjust the angle of the blinds, vertically spaced spindles alined with the top shaft and tilt rail and projecting through the intermediate partition, means connecting adjacent ends of the top shaft and tilt rail with corresponding ends of the spindles, and means in the side compartment arranged for manual operation to selectively rotate said spindles; the connecting means for the tilt rail being a detachable coupling including a floating head mounted on the adjacent spindle, a compression spring yieldably urging such head toward the adjacent end of said rail, and spaced pins on the head removably engaged in matching sockets in said rail.

7. A combination window and Venetian blind assembly comprising two relatively narrow compartments disposed edge to edge and separated by a substantially solid partition wall, a glass pane covering each face of one compartment, an access door covering one face of the other compartment and a fixed covering on the other face thereof, a Venetian blind assembly disposed in the glass covered compartment, operating means for the Venetian blind assembly enclosed in the other compartment, and said operating means including connecting means projecting through the partition wall and detachably connected in operative relation with the Venetian blind assembly.
